(57) **CLAIM**

The ornamental design for a glove, as shown and described.

DESCRIPTION

FIG. 1 is a front elevation view of a glove;

FIG. 2 is a back elevation view of a glove; and,

FIG. 3 is a top right-side perspective view of a glove.

The broken lines illustrate the article to which the claimed design is applied. The broken line subject matter forms no part of the claimed design.

1 Claim, 3 Drawing Sheets

FIG. 1

FIG. 2
